DESIGN FOR A BURNER

Leo R. Stark, Cedar Rapids, Iowa, assignor to
M. W. O'Riley, Cedar Rapids, Iowa

Application September 1, 1934, Serial No. 53,142

Term of patent 7 years

To all whom it may concern:

Be it known that I, Leo R. Stark, a citizen of the United States, residing at Cedar Rapids, in the county of Linn and State of Iowa, have invented a new, original, and ornamental Design for Burners, of which the following is a specification, reference being had to the accompanying drawings, forming part thereof.

Figure 1 is a front view in perspective of a burner showing my new design.

Figure 2 is a front view in perspective of the burner shown in Figure 1 but taken from the opposite side, and

Figure 3 is a front plan view in perspective of the burner shown in Figures 1 and 2.

I claim:—

The ornamental design for a burner as shown.

In witness whereof I hereunto subscribe my name this 28 day of August, 1934.

LEO R. STARK.
